UNITED STATES PATENT OFFICE

144,053

DESIGN FOR A BROOCH OR SIMILAR ARTICLE

Louis H. Goldstein, Providence, R. I., and Harry Lustig, New York, N. Y.

Application September 5, 1945, Serial No. 121,852

Term of patent 3½ years

(Cl. D45—19)

To all whom it may concern:

Be it known that Louis H. Goldstein and Harry Lustig, citizens of the United States, residing at Providence and New York city, respectively, in the county of Providence and State of Rhode Island, and in the county of Manhattan and State of New York, respectively, have invented a new, original, and ornamental Design for a Brooch or Similar Article, of which the following is a specification, reference being had to the accompanying drawing, forming part thereof.

Fig. 1 is a plan view of a brooch or similar article showing our new design.

Fig. 2 is a side elevation of a brooch or similar article showing our new design.

We claim:

The ornamental design for a brooch or similar article, substantially as shown.

LOUIS H. GOLDSTEIN.
HARRY LUSTIG.
